UNITED STATES PATENT OFFICE.

WALTER H. WARNER, OF SPRINGFIELD, MASSACHUSETTS.

DESIGN FOR A BADGE.

SPECIFICATION forming part of Design No. 16,975, dated November 2, 1886.

Application filed August 14, 1886. Serial No. 210,958. Term of patent 7 years.

To all whom it may concern:

Be it known that I, WALTER H. WARNER, a citizen of the United States, residing at Springfield, in the county of Hampden and State of Massachusetts, have invented and produced a new and original Design for a Badge, of which the following is a specification, reference being had to the accompanying drawing, forming a part thereof.

10 The drawing is a front elevation of my newly-designed badge.

The leading feature of my design consists in the representation in edge elevation of the wheel of a bicycle or of a similar vehicle having on its opposite sides and extending laterally and upwardly the representation of the wings of a bird, and having between the upper portions of said wings a curved frame extending across the periphery of said wheel,

15 and above said curved frame is the representation of one or more jewels. The aforesaid wheel is indicated by α , and the said wings—one on each side of said wheel—by the letters $c c$; and e indicates the circular frame between

the upper parts of said wings, and v indicates the aforesaid jewel or jewels at the upper edge of said frame. 25

I claim—

1. The design for a badge herein shown and described, the same consisting of the representation of a wheel, α , occupying a central position in the badge, and of the wings $c c$ —one on each side of the wheel—extending laterally and upwardly, and the curved frame e , extending between said wings over said wheel. 35

2. The design for a badge herein shown and described, the same consisting of the representation of a wheel, α , occupying a central position in the badge, and of the wings $c c$ —one on each side of the wheel—extending laterally and upwardly, and the curved frame e , extending between said wings over said wheel, and bearing upon its upper edge the representation of one or more jewels. 40

WALTER H. WARNER.
